DESIGN FOR A HAMMERING TOOL

Max Rubel, New York, N. Y.

Application May 10, 1938, Serial No. 77,089

Term of patent 3½ years

To all whom it may concern:

Be it known that I, Max Rubel, a citizen of the United States, residing at New York city, in the county of New York and State of New York, have invented a new, original, and ornamental Design for a Hammering Tool, of which the following is a specification, reference being had to the accompanying drawing, forming part thereof, in which:—

Figure 1 is a side view in elevation of a hammering tool, showing my new design;

Figure 2 is a rear view;
Figure 3 is a fragmentary front view in elevation; and
Figure 4 is a top plan view.

I claim:—
The ornamental design for a hammering tool, as shown.

MAX RUBEL.
